FURNACE WALL

Max H. Kuhner and Gustav A. Rehm, Worcester, Mass., assignors to Riley Stoker Corporation, Worcester, Mass., a corporation of Massachusetts

Application July 4, 1939, Serial No. 282 773

5 Claims. (Cl. 122—6)

This invention relates to furnace walls, and more particularly to walls of the type having a row of parallel metal tubes through which a suitable fluid is circulated to cool the wall.

Walls of this type are commonly used in steam boiler furnaces, the wall tubes being connected to the boiler so that water may be circulated through the tubes. Such a water cooled wall will absorb radiant heat very rapidly from the burning fuel, and large quantities of steam will be generated in the tubes. Under some circumstances it is desirable to limit the absorption of radiant heat so that the furnace temperature will remain high enough to ensure proper ignition and combustion of the fuel. For this purpose it has been proposed to cover the inner or heat exposed side of the water wall tubes with refractory material, but great difficulty has been experienced in securing such material in place against the tubes. This is particularly true in the case of water wall tubes which are rather closely spaced, since the refractory material cannot be satisfactorily interlocked with the tubes in such a construction.

It is accordingly one object of the invention to provide a comparatively simple and reliable construction for a fluid cooled furnace wall having a series of parallel metal tubes and means forming a shield to limit the absorption of radiant heat by the tubes.

It is a further object of the invention to provide a fluid cooled furnace wall having relatively closely spaced metal tubes and refractory material secured to the heat exposed side of the tubes in a simple and dependable manner.

It is a further object of the invention to provide a new and advantageous anchoring device particularly suitable for securing refractory material to the metal tubes of a fluid cooled furnace wall.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is an elevation of a fluid cooled wall, 50 viewed from the inner or furnace side;

Fig. 2 is a view similar to Fig. 1 but showing the wall before the application of refractory material thereto;

Fig. 3 is a section on the line 3-3 of Fig. 1: 55

Fig. 4 is a perspective view of an anchoring device;

Fig. 5 is a side elevation of the anchoring device; and

5 Fig. 6 is a perspective view, on a reduced scale, of a special wrench used in assembling the wall. The embodiment illustrated comprises a row of cylindrical metal tubes 10 arranged with their axes vertical and in a common plane, a relatively narrow space being provided between adjacent tubes. These tubes may form a part of a furnace wall, and water or other fluid may be circulated through them in a well-known manner to cool the wall and to absorb radiant heat from the furnace.

On the inner or furnace side of the tubes 10 we mount a series of blocks 11, preferably of a suitable heat resisting cast metal. Each block, as shown particularly in Fig. 10,

as shown particularly in Fig. 4, is substantially triangular in plan, with two concave cylindrical surfaces 12 converging outwardly and arranged to fit in close contact with the convex surfaces of two adjacent tubes 10. From the outer side of each block 11 there projects a fastening device in the form of a comparatively thin rectangular metal plate 14 located in a vertical plane and arranged to extend between the tubes 10 and for a substantial distance outwardly of the tubes. This plate 14 is held in place by

30 tubes. This plate 14 is suitably secured to the block midway between the concave surfaces 12, and for this purpose a hole 15 (Fig. 5) is provided through the plate near the inner end thereof, and the block is cast about this end of the plate in accordance with known foundry practice, the metal of the block flowing through the hole 15 so that when the casting has solidified the parts will be firmly and permanently locked together.

The plate 14 is made of a suitable malleable material, such as steel, adapted to be deformed by the application of sufficient force thereto. This property of the plate is utilized when the blocks are assembled on the tubes, the plates being inserted between the tubes, whereupon the outer end portions of the plates are twisted through an angle of approximately ninety degrees into a substantially horizontal plane, as shown in Fig. 3. As a result of this twisting of the plates, the blocks 11 are drawn into very firm contact with the tubes. To facilitate the twisting of the plates, we employ a special wrench shown in Fig. 6 and comprising an elongated heavy metal bar 17 having a slot 18 through the central portion thereof of the proper size to fit over the plates. The end portions 19 of the bar are

bent outwardly at a slight angle to avoid interference with the plates of blocks already in place on the tubes.

In some installations the blocks 11 may be placed closely together and they may by themselves afford sufficient protection to the tubes 10. However, in many cases it is desirable to install refractory material on the inner side of the tubes to reduce the transmission of heat to the tubes, thereby increasing the temperature in the furnace and facilitating the ignition of the fuel. When refractory material is to be used, the blocks 11 in each vertical row are spaced apart and the blocks in adjacent rows are staggered, as shown particularly in Fig. 2. In addition, projecting lugs 21 are formed on the inner faces of the blocks, these lugs being T-shaped, as best shown in Fig. 4. After the blocks have been mounted on the tubes, refractory material 23 is applied in plastic form over the inner side of the tubes and blocks. The T-shaped lugs 21 will be so interlocked with the refractory material as to retain the latter firmly in place.

It will be apparent that the invention provides a comparatively simple and effective construction for a furnace wall of the fluid cooled type, this wall including parallel metal tubes which can be shielded from the radiant heat to any desired extent. The tubes can be closely spaced, since the metal plates 14 are relatively thin. No welding of parts to the tubes is required.

Having thus described our invention, what we claim as new and desire to secure by Letters Patent is:

1. A furnace wall comprising a row of parallel cylindrical metal tubes with narrow spaces between them, blocks mounted on the inner side of the tubes and each having two concave cylindrical surfaces in contact with the surfaces of two adjacent tubes, and relatively thin plates of malleable metal extending outwardly from the blocks between the tubes, the outer portions of the plates being so twisted as to engage the outer surfaces of the tubes and to pull the blocks outwardly into firm contact with the tubes.

2. A furnace wall comprising a row of parallel metal tubes with relatively narrow spaces be-

tween them, blocks engaging the inner sides of the tubes, and comparatively thin plates of malleable metal extending outwardly from the blocks between the tubes, the inner portions of the plates adjacent the blocks being parallel with the axes of the tubes, and the outer portions of the plates being twisted into planes transverse to said axes to engage the outer surfaces of the tubes and to pull the blocks outwardly into firm contact with the tubes.

3. A furnace wall comprising a row of parallel metal tubes with relatively narrow spaces between them, blocks each having two concave cylindrical surfaces which converge in the outward direction and engage the inner sides of the tubes, and comparatively thin plates of malleable metal extending outwardly from the blocks between the tubes, the inner portions of the plates being located between the said converging surfaces and the outer portions of the plates being twisted into planes transverse to the axes of the tubes to engage the outer surfaces of the tubes and to pull the blocks outwardly into firm contact with the tubes.

4. A furnace wall element comprising a block having two concave cylindrical surfaces on opposite sides thereof and converging in the outward direction, the axes of said surfaces being parallel, and a comparatively thin plate of malleable metal secured to the outer portion of the block, the plate being located midway between said axes and parallel thereto, the plate extending at right angles with the plane of said axes and being adapted to be twisted to secure the block against the tubes of a furnace wall.

5. A furnace wall element comprising a comparatively thin plate of malleable metal and a metal block cast about the inner portion thereof and interlocked therewith, the block having two concave cylindrical surfaces located at opposite sides of the plate and converging in the outward direction, the outer portion of the plate being adapted to be twisted to secure the block against the tubes of a furnace wall.
